PHILIP G. BECKLEY, OF NEWARK, NEW JERSEY, ASSIGNOR TO FREDERICK STEVENS, OF SAME PLACE.

Letters Patent No. 74,280, dated February 11, 1868.

IMPROVEMENT IN SKATES.

The Schedule referred to in these Letters Patent and making part of the same.

TO ALL WHOM IT MAY CONCERN:

Be it known that I, PHILIP G. BECKLEY, of Newark, in the county of Essex, and in the State of New Jersey, have invented certain new and useful Improvements in Skates; and do hereby declare that the following is a full, clear, and exact description thereof, reference being had to the accompanying drawings, and to the letters of reference marked thereon.

In the annexed drawings, making part of this specification, A A' represent the foot-plates, and B the runner of a skate, the plates being attached to the runner by means of the connecting-pieces D. Between the plates and the runner, and running longitudinally of the skate, is a shaft, C, which has a right and left screw-thread cut upon it, the right thread on its forward end, and the left on its rear end. The extreme rear end of this shaft is made square in form, so that a key may be fitted to it for turning it. G G and H H represent elbow-levers, whose outer ends are turned up, with their inner faces corrugated for forming clamps for the sole of the boot or shoe. These levers are pivoted through their elbows to the under side of the foot-pieces, as seen at x x. The inner ends of these levers are semicircular. I I represent two nuts, which are provided with right and left threads to correspond with those upon the shaft. In the sides of these nuts are formed semicircular recesses, into which the inner ends of the levers H H and G G take and rest. The connecting-pieces D D have holes through them, through which the shaft C passes, but fitting loosely, so that it slides or moves endwise freely.

In securing this skate to the foot, the forward clamp on the levers H H may first be pressed up by the fingers of the operator, until they clasp the edges of the sole of the boot or shoe; the shaft C is then turned by means of a key for that purpose, until the clamps of levers G press against the heel. As soon as both sets of clamps begin to bear, they press equally until they are as tight as the operator desires them.

By this arrangement, I avoid the difficulty of a rigid connection between the front and rear clamps, in which the pressure in many cases is very unequal. With my arrangement the front clamps will not press the sole tightly until the rear clamps have moved up and embraced the heel. The moment one begins to press they both clamp equally. The front portion of the rear plate A' is turned up, as seen in Figure 2, to keep the heel in place, preventing it from moving too far forward.

Having thus fully described my invention, what I claim as new, and desire to secure by Letters Patent, is—

The clamp-levers G G and H H, in combination with the nuts I I, and the right and left screw-shaft C, constructed and operating as and for the purpose set forth.

In testimony that I claim the foregoing, I have hereunto set my hand, this 12th day of December, 1867.

PHILIP G. BECKLEY.
